METHOD OF ANALYZING VOLATILE MIXTURES

Glen S. Houghland, New York, N. Y., assignor to
The M. W. Kellogg Company, Jersey City, N. J.,
a corporation of Delaware

Application October 5, 1940, Serial No. 359,834

5 Claims. (Cl. 202—40)

This invention relates generally to the analysis of mixtures of volatile substances, and particularly to a method for determining the amount of a constituent in such a mixture when that constituent is (a) either the highest or the lowest boiling constituent of the mixture, neglecting mere traces of materials boiling respectively above or below it, and (b) is present in small amounts, and (c) has a boiling point close to that of the constituent boiling next below or above it respectively.

Although not limited thereto, the method of my invention is especially advantageous in analyzing mixtures of hydrocarbons, and may be of the greatest utility in providing control data for hydrocarbon fractionation systems. A case in point is the separation of iso-butane by fractionation from a mixture also containing normal butane and heavier hydrocarbons boiling in the gasoline range. Such a mixture is produced in the catalytic alkylation of iso-butane with butylene, it being desired to recycle unconverted iso-butane after separating it as completely as possible from the heavier alkylate and the non-reactive normal butane which is usually present. Due to the fact that there is only about 20° F. difference in boiling point between iso- and normal butane at the usual operating pressures, the control of a "de-iso-butane" is quite critical. It is highly desirable to have frequent analyses of the bottoms for iso-butane and of the overhead for normal butane, but the usual laboratory methods for obtaining such information are, besides being difficult to perform accurately, so time-consuming that results are available too late to be of value.

It is an object of the present invention to provide a method of analysis of the type described in the first paragraph of this specification which will give a rapid and, if desired, a continuous indication of composition. An additional object of the invention is to provide an efficient method of controlling a distillation column when one of the products of that column is a mixture of the type described in the first paragraph of this specification. Other objects will appear from the description of the invention hereinafter to be given.

In general terms the method of analysis of the invention comprises subjecting the mixture to be analyzed to fractionation and the establishment of a zone wherein the constituent analyzed for is present in a vapor and in a liquid in proportions greater than, but bearing a known relationship to, its proportion in the mixture under analysis and to the pressure and temperature in the zone. The apparatus of the inven-

tion whereby the above method may be carried out comprises, in general terms, a fractionating column having an inlet at one end and at the other end a device for changing a stream of fluid into a different fluid phase by adding or subtracting heat. In the event that the apparatus is to be used to analyze for the lowest boiling constituent in a mixture, the phase- and temperature-changing device will be a condenser; if the highest boiling constituent is to be analyzed for, it will be a reboiler. Remaining parts of the apparatus include a fluid outlet at the same end of the column as the inlet and pressure and temperature indicating devices connected to the interior of the enclosed space at various points.

The annexed drawing is a diagrammatic elevation of one form of the apparatus of the invention whereby one embodiment of the analytical method of the invention may be practiced. Reference will now be made to the drawing for a more detailed explanation of the invention. The apparatus shown in the drawing has been provided with all necessary means for carrying out analyses for both heaviest and lightest constituents of mixtures. It is to be understood, therefore, that if only one type of mixture is to be analyzed, certain of the elements shown can be dispensed with, as they are then inoperative.

In the drawing, 1 is a fractionating column provided with plates, baffles, packing or other means of insuring adequate vapor-liquid contact, packing being preferred in the small column sizes which will normally be chosen. The diameter of the column will be fixed by the size of the sample to be analyzed, and will seldom exceed four inches. The height of the column will depend upon that characteristic of the filling known as the "height equivalent to one theoretically perfect plate," and upon the difference between the boiling point of the constituent analyzed for and that of the constituent boiling next adjacent thereto. Sufficient height to provide the effect of about 25 theoretical plates will be adequate for most purposes.

45 The base of the column 1 is provided with a vapor inlet 2 controlled by a valve 3 and with a reboiler coil 6 regulated by valve 7. This coil is intended to be supplied with steam as a heating medium but may be supplanted by an electrical heating element if desired. A line 4 controlled by valve 5 affords means of withdrawing liquid from the base of the column.

The top of the column has a liquid inlet 10 regulated by a valve 11 and a vapor outlet line 12 leading to a block valve 13 and a pressure con-

trol valve 14, whence it is vented. Branching from line 12, line 15 leads to a block valve 16 and thence to a condenser 17, to which a refrigerant is supplied via line 18 in an amount regulated by valve 19. The outlet of the condenser 17 is connected to line 20 which is blocked by valve 21 and leads back to the top of the column. 8 and 22 and 9 and 23 are thermometer or thermocouple wells and pressure gauges respectively, the exact location of which will be determined by the analyses for which the apparatus is to be used.

Because of the fact that different types of analyses require different column heights for optimum results, I may provide the column 1 with a series of vapor and liquid inlets and outlets at spaced intervals in lieu of lines 11, 12 and 21 so that any desired portion of the tower may be used.

The apparatus shown in the drawing is adapted to manual control, but in practice it will facilitate operation to provide automatic flow and liquid level controllers at various points which will be readily recognized from the hereinafter given description of the manner in which the apparatus is operated. A vapor trap on the liquid outlet 4 will also be helpful.

The operability of the method and apparatus herein disclosed in giving information which will be indicative of the amount of a component in a mixture arises from the fact that if the percentage of one component in a volatile mixture is varied while the relative proportions of other components remain constant, the vapor pressure of the mixture at any given temperature will vary proportionately, or conversely, the temperature at which the mixture will have a given vapor pressure will vary proportionately. This fact is constantly made use of in conventional methods of controlling distillation processes not involving the precise separation of closely boiling constituents, as the temperatures at the top and bottom of a column under a given pressure are then sufficiently sensitive indices of the composition of the top and bottom products. When an interval as small as 20° F. between the boiling points of constituents to be separated is encountered, however, and when as little as 1% of one constituent is to be left in the residue, this fact does not alone afford sufficient precision of control. For example, it was found in one instance that a change of only 1° F. at the bottom of a column corresponded to a 100% increase in the iso-butane content of the bottoms products, i. e. from 1% to 2%. It is not commercially practicable to control bottom temperature within 1° F.

The manner in which the apparatus shown in the drawing is operated pursuant to my method of analysis will now be described with reference to the determination of the per cent iso-butane in a mixture of iso-butane, normal butane, and heavier hydrocarbons. During such a determination, valves 1, 11, and 13 will remain closed, and the reboiler 6 will be inoperative.

To begin, a stream of the sample under analysis is passed into column 1 through line 2 at a constant rate and in a completely vaporized condition. The rate of introduction is dependent upon the size of the column, from 2 to 5 gallons (liquid) per hour being about right for a 3 inch column packed with tile saddles. The entering vapors rise through the column and pass through line 12 to line 15 and into the condenser 17 where they are liquefied. The resultant liquid returns through line 20 to the top of column 1

and flows back down therethrough in counter-current contact with the rising vapors, being finally withdrawn at the bottom through line 4.

As soon as liquid downflow is established, there will be a tendency for the low-boiling iso-butane to collect in the upper portion of the column. The vapor stream leaving the column will contain iso-butane which, after return to the column as liquid through line 20, is selectively re-vaporized by the heat of the rising vapors and driven overhead again. No vapor is allowed to escape at the bottom through line 4, and after the air originally present has been purged from the apparatus by opening valve 13 for a short time, the pressure in the apparatus will be fixed by the temperature to which the liquid leaving condenser 17 has been cooled. Any pair of co-existent values of the temperature and pressure at the outlet of the condenser 17 will be indicative of the per cent iso-butane in the condensed liquid, of which the remaining portion will be normal butane. As a matter of fact, the temperature and pressure at any point will be indicative of the per cent iso-butane in the streams flowing through the column at that point. It will be understood by those skilled in the art of distillation that there will be a continuous change in the iso-butane content of the vapor and liquid streams traversing the tower, and that this content will be at a maximum at all points above the top of the packing in the tower, including the reflux circuit. Now, if the column 1 is made very high, the liquid and vapor respectively entering and leaving the top of the column will be very high in iso-butane content, or even 100% iso-butane, while if the column is relatively short the iso-butane content at its top will not be much greater than that of the sample. The result desired, however, is that there be a point in the column where the pressure and temperature reflect a change in iso-butane content with the greatest sensitivity, and this will be so at a point where the iso-butane content is nearest to 50 mol per cent, although any point where the iso-butane content is between about 30 and 70 mol per cent will afford sufficient sensitivity for a less precise determination. I therefore preferably make the column at least high enough for the iso-butane content to rise as high as 50 mol per cent at the top thereof. Additional height is of no advantage, and as previously mentioned can be nullified by connecting the lines 12 and 21 to the column at the optimum height. In the example under discussion, a height equivalent to about 16 theoretical plates will be the optimum, and will correspond to a column height of approximately 15 feet when the saddle packing is used.

With any given column height, the per cent iso-butane at all points will vary with the iso-butane content of the sample. I therefore make the column of such a height that the average iso-butane content of the material under analysis, or better the desired iso-butane content in the case of a fractionating column product, will produce a 50% concentration at the top. By providing a 25 or 30 theoretical plate column having a series of inlets and draw-offs at various heights I may accommodate any material likely to require analysis.

Having established a zone in the column 1 where the pressure and temperature at any point accurately reflect iso-butane content at that point, the actual determination of iso-butane content at that point is relatively simple. All

that is necessary is to refer to a pressure-temperature-composition diagram for the binary system under consideration, which may be constructed either from published data, calculated by means of Raoult's law, or calculated from the fugacities or equilibrium constants of the constituents. Such calculations are well known to those skilled in the art of distillation and need not be enlarged upon herein.

Since the concentration of iso-butane in the upper portion of column 1 results from a fractionation at constant (total) reflux, the relationship between the composition of the liquid at any point in the column and that of the sample is fixed by the degree of fractionation performed by the column packing between that point and the sample inlet.

If the efficiency or "height equivalent to one theoretical plate" of the column packing is known from previous experiments then from the composition of the liquid or vapor at any point in the column it is possible to calculate the composition of the feed, i. e. the sample under analysis. The so-called "tray to tray" calculation required is also well known to those skilled in the art and need not be given in detail.

In the event that the efficiency of the packing, plates or baffles desired to be used is not known, then the relationship between sample and column top compositions may be established by preliminary experiments, employing the usual laboratory method of analysis to obtain the necessary data on compositions. This will seldom be necessary, however, as a variety of packing materials are available of which the efficiencies have been determined over a wide range of conditions. The relationship between temperature, pressure and composition for any given apparatus and type of analysis is capable of being embodied in a chart or nomograph, the preparation of which is well within the ability of one skilled in distillation processes. Such a chart will greatly simplify the use of the method in controlling full-scale distilling operations.

Even when the efficiency of a packing is known, somewhat greater accuracy is attainable by actual calibration of the apparatus, correcting the calculated results by comparing them with analyses made in the usual manner.

Obviously, the use of the method and apparatus will be made easier by fixing the temperature at the top of the column and allowing only the pressure to vary. This may be accomplished if desired by connecting a temperature-responsive element located in line 20 to position valve 19. Optionally, a pressure-responsive element could be so connected, in which case only the temperature would vary.

A complementary procedure will now be described with reference to the drawing whereby an analysis may be made when the highest boiling constituent of a mixture is to be analyzed for. A typical sample would be the overhead product of the same distillation of which the previously discussed material was the bottoms, that is, a mixture of a large amount of iso-butane with a small amount of normal butane. In analyzing such a sample in the apparatus shown, valves 3, 5, 16, 19 and 21 remain closed and valve 13 remains open.

I introduce a liquid stream of the material under analysis into the tower through line 10, and allow it to flow down through the tower to the reboiler coil 6. Sufficient heat is supplied to the reboiler to completely vaporize all liquid

reaching it, suitably by means of liquid-level control of valve 1. The vapors produced pass back up through the column in counter-current contact with the down-flowing liquid and leave the column via line 12. A suitable constant pressure in the column is maintained by the pressure control valve 14.

As soon as vapor up-flow is established, there will be a tendency for the high-boiling normal butane to collect in the bottom of the column to the exclusion of iso-butane. The reboiled vapors will contain normal butane which, on cooling by contact with the down-flowing liquid will be preferentially condensed and returned to the bottom again. The pressure on the column having been fixed by adjustment of valve 14, the reboiler will supply heat enough to generate that pressure while vaporizing the down-flowing liquid. The temperature (and pressure) at all points in the column below the entrance of line 10 then become sensitive indices of the compositions at those points in proportion to the approach of the normal butane content at those points to 50 mol per cent.

The distance between the point at which the feed is introduced and the point at which the normal butane content approaches 50 mol per cent is again a function of the efficiency of the packing, and may be calculated or determined by experiment. It may be well at this point to mention that packing efficiencies depend to a certain extent on the rate at which vapor and liquid are passing, and that constancy of feed rate is important to the accuracy of the method herein disclosed. Calibration should obviously be done at the same feed rate as is contemplated in the actual analyses.

As might be expected, I find that approximately the same number of theoretical trays are necessary to get 50 mol per cent normal butane concentration at the bottom of the tower when analyzing for normal butane in iso-butane as are necessary in the type of analysis first described. The reason for this is that the difference between the boiling point of the constituent analyzed for and that of the next adjacent constituent is the controlling factor.

Except for the fact that the temperature and pressure are preferably observed near the bottom instead of at the top of the column, the manner of obtaining the final analytical data in this second type of operation is exactly analogous to that described with reference to the first.

It will be appreciated by those skilled in the art that if, in the first type of operation, the temperature is observed at any point beyond the condenser 17 in line 20, the effect of one more theoretical tray will be obtained as compared to an observation taken ahead of the condenser in the vapor stream traversing lines 12 and 15. This effect has to be taken into account in calibrating or calculating the column.

When analyzing the bottom product of a full-scale distillation as first described, I prefer to take a sample in vapor form directly from the vapor space below the bottom tray of the full-scale column, passing it directly to line 2 and taking precautions to prevent condensation en route. If desired, however, it is entirely feasible to take a liquid sample of the full-scale column bottoms and to pass this liquid through a vaporizer before introducing it into line 2. Similarly, in analyzing a top product I prefer a liquid sample taken from the reflux accumulator or from the top tray of the full-scale column.

It is to be understood that my method is applicable to the analysis of bulk mixtures (taken from storage, for example) as well as of product streams issuing from processes. My method should not be confused with prior analytical methods wherein a miniature distillation column is used, and in which the procedure comprises exhaustively fractionating a sample of known weight or volume in order to separate and make possible the volumetric or gravimetric measurement of 100% of the constituent analyzed for. In my method there is no separation of a pure component, in fact not over 50% concentration of any component is aimed at.

The presence in a sample stream of traces of a constituent boiling outside (i. e., respectively above or below) a high or low boiling constituent to be analyzed for, while very undesirable, is not necessarily sufficient to defeat the method of my invention. For example, if very small traces of propane are present in a sample to be analyzed by the first procedure described, I vent the column periodically through line 12 to prevent the accumulation of propane in the top section. Likewise I may bleed off accumulated pentane 25 from the bottom when operating in accordance with the second type of procedure.

For obvious reasons, the method of my invention should be carried out as nearly adiabatically as possible. To this end careful insulation 30 and/or jacketing of the apparatus are advisable.

I claim:

1. A method of determining the amount of a minor constituent in a mixture of distillable substances, said constituent boiling substantially at one extreme of the boiling range of said mixture and having a boiling point close to that of the constituent boiling next within said extreme, which comprises introducing a fluid stream of said mixture into one end of an elongated countercurrent contacting zone of known contacting efficiency, causing said stream to flow to the opposite end of said zone, altering the temperature of said stream at said opposite end to convert it completely into a different fluid phase, causing the whole of the changed phase stream to flow back through said zone in countercurrent contact with the original phase stream, and then withdrawing said changed phase stream from said zone, whereby the pressure and temperature of either of said flowing streams at any point in said zone are made joint indices with the efficiency of said zone of the amount of said minor constituent in said mixture and measuring the temperature and pressure at some point in said zone.

2. A method as in claim 1 wherein said concurrent contact is made of sufficient duration and intimacy to concentrate said minor constituent in said streams to at least 30 mol per cent at some point in said zone.

3. A method as in claim 1 wherein said countercurrent contact is made of sufficient duration and intimacy to concentrate said minor constituent in said streams to approximately 50 mol per cent at some point in said zone and wherein said measurement of temperature and pressure is made at said point.

4. In the column distillation of a volatile mixture the boiling point of one constituent of which is close to the boiling point of a constituent boiling next adjacent thereto, it being desired that one of the products of said distillation shall contain a maximum of one of said constituents and a minimum of the other, the improvement which comprises continuously withdrawing from the distillation column a stream of fluid of substantially the same composition as said product, introducing fluid thus withdrawn into one end of a separate fractionating zone of known inherent fractionating characteristics, causing said fluid to flow to the opposite end of said zone, altering the temperature of said fluid to convert it into a different fluid phase, and then causing the whole of the changed phase fluid to flow back through said zone in countercurrent contact with original fluid as yet unchanged in phase, and then withdrawing said changed phase fluid from said zone, whereby the pressure and temperature at any point in said zone appreciably distant from the point of introduction of said original fluid are through the known fractionating characteristics of said zone made indices of the amount of the constituent desired to be excluded from said product contained in the original fluid, measuring the temperature and pressure at some point in said zone and regulating said column in accordance therewith.

5. A method of determining the amount of a minor constituent in a mixture of distillable substances, said constituent having a boiling point lower than any constituent present as more than a trace in said mixture but close to that of the constituent boiling next above, which comprises introducing a vapor phase stream of said mixture into the lower end of a fractionating column of known inherent vapor-liquid contacting efficiency, flowing said vapor stream up through said column, cooling said vapor stream to convert it into a liquid stream, passing the whole of said liquid stream downwardly through said column in countercurrent contact with said vapor stream, and withdrawing said liquid stream from said column, measuring the temperature and pressure at any point in said column appreciably distant from said lower end and using said measured temperature and pressure and said known column efficiency as joint indices from which to calculate the amount of said minor constituent in said mixture.

GLEN S. HOUGHLAND.

CERTIFICATE OF CORRECTION.

Patent No. 2,299,899.

October 27, 1942.

GLEN S. HOUGHLAND.

It is hereby certified that error appears in the printed specification of the above numbered patent requiring correction as follows: Page 4, first column, line 57-58, claim 2, for "concurrent" read --countercurrent--; page 4, second column, line 21, claim 4, for "fllow" read --flow--; and that the said Letters Patent should be read with this correction therein that the same may conform to the record of the case in the Patent Office.

Signed and sealed this 1st day of December, A. D. 1942.

Henry Van Arsdale,
Acting Commissioner of Patents.
